CHARLES B. MOORE, OF EVANSTON, ILLINOIS, ASSIGNOR TO AMERICAN ARCH COMPANY, OF NEW YORK, N. Y., A CORPORATION OF NEW YORK.

LOCOMOTIVE-BOILER FURNACE.

1,115,957.

Specification of Letters Patent.

Patented Nov. 3, 1914.

Application filed February 14, 1912. Serial No. 677,565.

To all whom it may concern:

Be it known that I, CHARLES B. MOORE, a citizen of the United States, and a resident of the city of Evanston, county of Cook, and State of Illinois, have invented certain new and useful Improvements in Locomotive-Boiler Furnaces, of which the following is a specification.

My invention relates to improvements in locomotive boiler furnaces and has particular reference to refractory deflecting walls or baffles commonly called arches for use in the fireboxes of locomotive boilers.

The general objects of my invention are to provide a refractory arch for installation and use in a locomotive boiler furnace, which can be easily and quickly installed in a locomotive firebox; which shall be of relatively light weight and low cost and parts of which can be conveniently removed for effecting repairs upon the side sheets of the firebox; and which shall be of such form that it will materially enhance the admixture and commingling of the firebox gases.

A particular feature of my invention is to provide an arch which shall be wholly constructed of refractory members and which shall be in a sense self-supporting in the firebox.

My invention consists in the several improvements, the various combinations of elements and the associations of parts whereby the above and other objects are attained and all as hereinafter described and pointed out in the claims.

My invention will be more readily understood by reference to the accompanying drawings forming part of this specification, and in which:

Figure 1 is a central longitudinal section of a firebox equipped with an arch embodying my invention; Fig. 2 is a horizontal section of the firebox on the line 2—2 of Fig. 1; Fig. 3 is a vertical transverse section of the firebox on the line 3—3 of Fig. 1; Fig. 4 is an enlarged detail portion of the arch illustrating a section similar to the section of the arch shown in Fig. 1 and illustrating one of the important features of the invention; Fig. 5 is an enlarged detail transverse section on the line 5—5 of Fig. 2 taken

through one of the refractory supporting spans.

I have chosen to illustrate my invention as embodied in a so-called front arch, but it should be evident that my invention is capable of being embodied in arches occupying other positions and having slightly varying functions, and therefore my invention should not be limited to this specific form of arch. So-called front arches usually occupy an upwardly and rearwardly inclined position in the forward end of the firebox in contact with or close to the flue sheet and serve to baffle and deflect the firebox gases in their flow upwardly through the firebox from the fuel bed to the flues. The deflection of the firebox gases not only serves to retain them in the firebox a sufficient time to allow complete combustion to take place, but also causes them to flow backward and forward in the firebox and thereby distribute their heat throughout substantially the whole interior surface of the firebox. A refractory front arch made in accordance with my invention not only retains the above desirable features but also serves to materially enhance the admixing and commingling of the firebox gases and thereby adds to the fuel efficiency of the boiler.

A locomotive boiler firebox as shown in the drawings comprises a flue sheet 2 at its forward end, side sheets 3, 3, a rear sheet 4 having a fuel door or opening 5 and a crown sheet 6. The firebox is provided with a grate 7 and flues 8 lead forward from the flue sheet.

My improved firebox arch is composed wholly of refractory members. It spans the firebox transversely and is supported upon and by the side sheets of the firebox. The arch is built up of two kinds of refractory bricks or members, one kind being span or supporting members and the other kind being cover or arch members. The span members 10 are elongated bricks somewhat T-shape in form but inverted in position; that is, the head of the T is at the lower edge of the brick. These bricks are arranged in pairs transversely of the firebox and each of these pairs is longer than the width of

the firebox and the bricks of the pair are arranged in upwardly and inwardly inclined positions in the form of a span or of a subsidiary supporting arch and are in a sense self-supporting. These bricks are provided with sockets 3^a at their outer and lower ends adapting the bricks to be supported upon lugs 3^b secured in proper positions to the side sheets of the firebox. The inner or contacting ends of these supporting or span members are formed for substantial interlockment with each other and they thereby mutually retain each other in position. The bricks 10 as shown in the drawings are provided with complementary projections and sockets 10^a and 10^b, respectively, upon their inner or abutting ends, which serve to interlock these abutting ends together and prevent both vertical and lateral relative movement of these ends of the bricks. These bricks as stated are somewhat T-shaped in cross section and the head 10^c of each brick is at the lower edge. These bricks are relatively deeper than they are wide and form what may be termed light arch trusses extending across the firebox from side sheet to side sheet. I make these span or truss members of such dimensions that they are strong enough not only to carry their own weight but also to bear the additional weight of the cover or arch bricks 11. The heads 10^c of the truss members provide supporting shoulders or flanges 12 adjacent to the lower edges of these trusses and these flanges serve as supports for the cover bricks 11. These cover bricks are substantially rectangular in form and are relatively thin. They are long enough to reach from one of the refractory spans to the adjacent one and are provided with flanges 13 at their ends adapted to rest upon the flanges or shoulders 12 of the span bricks and the lower portion of these cover bricks project downwardly between the span bricks substantially flush with the lower edges of the span bricks. In other words, the cover bricks are provided with grooves or sockets 14 for receiving the flanges 12 of the span bricks. I sometimes lighten the cover bricks by providing their under surfaces with shallow gas-mixing pockets or recesses 15 which occupy nearly the whole area of the brick and thereby not only make the bricks light in weight but provide the arch with a plurality of subsidiary gas-mixing pockets and with a plurality of gas deflecting surfaces arranged at various angles. The cover bricks being arranged substantially flush with the lower edge of the span bricks serve as guards to prevent the rapid destruction of the span bricks as the firebox gases are prevented from impinging directly against the side surfaces of these members.

By reference to Fig. 4 it will be noted that the side surfaces of the span bricks 10 are curved and I curve them on a radius substantially equal to their distance apart or, in other words, equal to the length of the cover bricks which are to be placed between the span bricks. This is clearly indicated by the dotted position of the cover brick, its lower end being raised from its normal position and the brick itself being supported on the curved surface with its upper end substantially in contact with the upper span brick. It has been found that the fireman in operating the heavy pokers or tools used at times for breaking up the fuel bed, sometimes, particularly in short fireboxes, accidentally strikes the cover bricks from beneath and displaces them from their positions, in which case the fire bricks fall from the arch to the fuel bed and the efficiency of the arch is thereby decreased. To overcome this difficulty I have provided the arch herein described in which the cover brick when it is raised, as indicated by dotted lines in Fig. 4, will not be displaced from its position to such an extent but that it can immediately return thereto and will be returned by gravity and to cause it to thus return freely to its position, I curve the side surfaces of the span bricks 10. In other words, the brick having been struck from beneath and raised to occupy the position shown by dotted lines will immediately thereafter descend to its proper position, the lower end of the brick sliding down upon the curved surface of the arch brick upon which it rests and the cover brick will be thereby guided into its proper normal position.

The arch as described comprises two inwardly and upwardly inclined leaves each thereof being composed of several of the span bricks separated by rows of the cover bricks and for the purpose of being able to install these arches in fireboxes which vary slightly in width and with supporting or span bricks of substantially the same length, I make the span bricks of such a form that they will find solid and substantial bearing upon the side sheets even though it may be necessary to arrange them at different angles to compensate for different widths of fireboxes. In other words, I round the outer ends 16 of the span bricks vertically, as shown in Fig. 5, so that these bricks will contact solidly with the side sheet at whatever angle it is found desirable to place them, and consequently the outer ends of these span bricks are preserved against fracture due to abnormal strains.

In building refractory arches in accordance with my invention, I first secure the arch supporting lugs to the side sheets in

proper spaced relation to receive the span bricks of the arch. I then place the lower span of the arch in position, placing the sockets of the span bricks upon the supporting lugs and abutting the two bricks of the span together in interlocked relation and leaning against the flue sheet. Thereafter, I place a second span or subsidiary arch in position above the first supporting it upon its supporting lugs, and I hold this second span in position longitudinally of the firebox spaced from the first span by means of the cover or arch bricks. These cover bricks are usually of such a width that it requires several of them to completely fill the space between the adjacent subsidiary arches. I place the cover bricks in position by lowering one edge, preferably the lower edge, into position upon the flange of the lower span and then I lower the upper end down upon the flange of the upper span, the cover bricks turning upon the lower span as upon a pivot and the upper edge sweeping past the curved surface of the upper span during this movement. The cover brick once being in position cannot be jarred or moved out of place and when one end is accidentally lifted, gravity will immediately and automatically replace it in its normal position. The curved surfaces of the span bricks not only overlap the ends of the cover bricks and thus prevent them from moving bodily upward and becoming free from their supports, but they also serve, as has been stated, to guide the cover bricks when one or the other end thereof is moved up or down. It sometimes occurs that an arch as thus far described consisting of two of the spans and one transverse row of the cover bricks is of sufficient length to accomplish the results in fuel economy which are desired, but usually it consists of a sufficient number of these subsidiary spans separated and held in position by transverse rows of the cover bricks to position the rear end of the arch about the middle of the firebox. The dimensions of the span bricks, other than their length, are controlled by the features that they shall not be too heavy to be readily placed in position and that they shall not be of such size but that they can be readily passed into the firebox through the fire door. The dimensions of the cover bricks are limited by the same features.

It will now be evident that my improved arch which I support upon the side sheets of the firebox without any additional supports, can be readily placed in the usual firebox without laborious or costly preparations, and as it consists of a plurality of comparatively small members, it can be built with the expenditure of little time and labor. Furthermore the arch once having

been built is protected against accidental destruction due to the displacement of the arch bricks by the fire tools in the hands of the fireman.

As many modifications of my invention will readily suggest themselves to one skilled in the art to which it appertains, I do not confine the same to the specific structures herein shown and described.

Having thus described my invention, I claim as new and desire to secure by Letters Patent:

1. A locomotive boiler firebox, in combination with an inclined refractory arch therein, comprising a plurality of V-shaped, self-supporting refractory spans, and a transverse row of cover bricks interposed between the lower edges of said spans and supported thereby, each of said cover bricks being free to turn upon either end as upon a pivot, the adjacent side surfaces of the span bricks being curved to guide the cover bricks in their movement to and from their normal positions.

2. A locomotive firebox, in combination with an inclined front arch therein comprising relatively deep, elongated refractory span members, arranged in pairs transversely of the firebox and supported by the side sheets thereof, supporting flanges on the lower edges of said span members, cover bricks resting on said flanges and extending between adjacent spans, the side surfaces of said span members above the supporting flanges being curved on a radius equal to the length of the cover bricks.

3. A locomotive boiler firebox, in combination with an inclined refractory front arch comprising pairs of refractory supporting members spanning from side sheet to side sheet supported thereby and spaced apart, said supporting members having horizontal supporting flanges projecting horizontally from their lower edges, cover bricks interposed between said supporting members and held thereby in inclined position, the cover bricks being free to swing out of their normal position upon their upper ends as upon pivots and the span having inclined side faces to support the cover bricks with their upper ends in proper contact with the adjacent span member, whereby the cover bricks can return freely to their normal positions.

4. A locomotive boiler firebox, in combination with an inclined refractory front arch therein, comprising elongated span members, T-shaped in cross section, the heads thereof being arranged at the lower edges of the span providing cover brick supporting flanges, the bodies of the supporting members being thickened at their upper edges thereby providing cover brick receiving spaces which are narrower at their up-

per parts than at their lower parts to retain cover bricks against displacement and cover bricks arranged between the lower edges of the span members resting upon the supporting flanges and maintaining said spans in spaced relation.

In testimony whereof, I have hereunto set

my hand, this 24th day of January, 1912, in the presence of two subscribing witnesses.

CHARLES B. MOORE.
